UNITED STATES PATENT OFFICE

PAUL E. SCHLEICHER AND WALTER C. CALCOTT, OF GARY, INDIANA, ASSIGNEES TO
SCHLEICHER, INC., A CORPORATION OF ILLINOIS

RADIATOR HOOD

Application filed February 6, 1928. Serial No. 252,080.

This invention relates to a radiator hood and concerns itself with a structure that can be far more cheaply and economically manufactured than heretofore. To this end and to enable quick and effective assembly, the parts are stamped from sheet metal.

The invention comprises the novel structure and combination of parts hereinafter described and more particularly pointed out and defined in the appended claims.

In the accompanying drawings, which illustrate a preferred embodiment of this invention and in which similar reference numerals refer to similar features in the different views:

Figure 1 is a perspective view of a radiator hood involving this invention.

Figure 2 is an enlarged sectional view taken upon the line II—II of Figure 1.

Figure 3 is a top plan view of the radiator hood with the cover removed and with parts broken away.

Figure 4 is an enlarged fragmentary sectional view taken upon the line IV—IV of Figure 1.

Figure 5 is an enlarged sectional view taken upon the line V—V of Figure 4.

Figure 6 is an enlarged fragmentary sectional view thru the end door of the hood.

Figure 7 is an enlarged sectional view taken upon the line VII—VII of Figure 1.

Figure 8 is an enlarged sectional view taken upon the line VIII—VIII of Figure 1.

Figure 9 is an enlarged sectional view taken upon the line IX—IX of Figure 8 with parts in elevation and parts in section.

Figure 10 is an enlarged sectional view taken upon the line X—X of Figure 3.

The different parts of the radiator hood are stamped from sheet metal to provide standard parts which may be readily assembled to provide a rigid and durable hood, and, as many of the parts are similar in design, it will only be necessary to specifically describe one of each of the different parts.

The four corner parts 1 of the radiator hood are similar and each consists of a sheet metal plate which is stamped into the form of an angle as shown in Figures 1 and 4. The apex of the angle constitutes a corner. The

legs or flanges 1a and 1b of each corner post have inturned terminal edges 2 to provide an abutment surface, and inward of such abutment surface there is a groove 3 which is likewise formed by stamping. Each abutment surface 2 is suitably slotted at upper and lower points, as indicated at 4, for a purpose that will later appear.

Where a short hood is required, the four corner posts will be sufficient to support the structure. However, when a longer hood is required, consisting of two or more panels, one or more intermediate posts are desirable. In the present instance, the hood is shown as consisting of two panels 5 with an intermediate post 6, which is shown in sectional form in Figures 8 and 9. It will be noted that the intermediate post 6 is also stamped from sheet metal, but it is stamped into the form of a channel wherein the web 6a constitutes the outer part of the post and the flanges 6b constitute abutment surfaces. Beyond the flanges 6b, or rather inwardly thereof, are grooves 3 which are stamped in the post as a manner similar to the corner posts. The abutment surfaces 6b are provided with upper and lower slots 4 just as the corner posts.

Upper and lower longitudinal molding rails 7 extend between the front posts of the hood, and the rear corner posts are connected to the front corner posts by lateral rails 8. It might be here mentioned that the rails 7 and 8 are similar except as to their length, so that they can be cut from the same stock. These rails are stamped from sheet metal, and the cross-sectional form thereof is shown in Figure 7. It will be noted that each rail is substantially in the form of a channel, the web of which constitutes the main outer surface of the rail and the flanges 9 form the edges thereof. Inwardly of each flange 9 there is a groove 10 which is stamped in the rail. The walls of the groove 10 overhang the interior margins of the rails. A suitable anchor lug 11 is stamped from the wall of each groove 10 adjacent each end for a purpose to be presently described.

The manner of anchoring or securing the rails to the posts will now be set forth. It will be noted, as before related, that the walls

of the grooves 10 in the rails overhang the interior margins of the rails to a considerable extent. An inspection of Figure 7 will show that the rails are substantially rectangular tubes, which are open between the grooves 10. 5 Anchor members 12 fit in the hollow ends of the rails. Each anchor member 12 is formed by bending a piece of sheet metal into substantially rectangular form corresponding with the interior of the rails. The free edges 10 of the sheet of metal may be brought together, as shown in Figure 8. Each anchor member 12 is formed with suitable lugs 13 for engagement with the lugs 11 on the walls of the grooves 10. Each anchor member 12 is also provided with a terminal tenon 14 extending into a slot 4 in the post. The sides of the tenons 14 are open, in order that a wedge 15 may be inserted therethrough for firmly drawing the ends of the rails into abutting relation with the abutment surfaces 2 of the posts. These tenons may also be provided with beads 14a for coaction with the wedges. 15

In Figures 8 and 9, which illustrate the construction of an intermediate post, it will be noted that the wedges 15 are joined and comprise the arms of a U-shaped member, and in Figure 5 the upper wedge 15 is shown as attached to a downwardly extending arm which affords sufficient weight to hold the wedge in place, while the lower wedge 15 is provided with an arm 16 adjustably attached to a bolt 17 that holds the foot 18 upon the post. It might be here mentioned that the 20 posts are generally provided with suitable feet for supporting the same upon the floor. 30

The back wall of the hood is generally formed of a sheet metal plate 19, best shown in Figure 4. The terminal margins of the back 19 are provided with folded margins 20 which abut the abutment surfaces 2 of the posts. These folded margins are attached to the posts by a hollow tenon 21 which has a tang 22 extended thru the flange 20 and crimped thereover. The tenons 21 extend thru slots in the rear posts and wedges 15 extend thru such tenons. The rear plate may, of course, be provided with any desired number of tenons for firmly securing the same to 40 the rear posts. 50

In the illustrated embodiment of this invention, the hood is shown as having a pair of sliding doors 23 and 24 at one end. Each door is provided with a suitable operating knob 25 whereby the doors may be opened for access to the end valves of the radiator covered thereby. The lateral margins of the doors 23 and 24 slide in the grooves 3 of the end posts and, to prevent rattling, a leaf spring 26 may be attached to the upper margin of the door 23 and to the lower margin of the door 24. When the doors are closed, these spring pressed or remote margins are in the grooves 10 of the rails 8, and the 60 springs 26 frictionally retain the same. The 75

adjacent ends of the doors preferably overlap, as indicated at 27 in Figure 10. When access is desired to either the upper or lower end of the radiator, the corresponding door is operated by a sliding movement into superposed relation with the other door. 70

A water pan 28 is suspended in the top of the hood over the top of the radiator. The pan is supported upon a pair of transverse hangers 29, which have rear, hook-shaped ends engaging the upper end of the back plate 19, and front, hook-shaped ends engaging the top edge of the inner wall of the upper groove 10 of the upper rail 7 (Fig. 7). A suitable removable cover 30 fits over the top of upper rails and posts for forming the top closure of the hood. 75 80

The aforementioned panels 5 are assembled with their lateral margins in the grooves 3 of the posts and their upper and lower margins in the grooves 10 of the rails. For this purpose, the grooves 10 of the rails lie in the same plane as the grooves 3 in the posts. 85

From the foregoing, it will be appreciated that the parts of the hood may be readily stamped from sheet metal in a very few operations. The corner posts 1 are the same and each requires a similar operation in manufacture. Likewise, the rails 7 and 8 are of the same cross-section and may be cut from the same stock. Furthermore, these posts can be easily and quickly assembled with the panels, consequently the cost of manufacture and production is materially reduced. 90 95

We are aware that many changes may be made, and numerous details of construction may be varied through a wide range without departing from the principles of this invention and we, therefore, do not purpose limiting the patent granted hereon otherwise than 100 necessitated by the prior art. 105

We claim as our invention:

1. In a radiator hood, a pair of sheet metal posts having abutment surfaces and grooves inwardly of said surfaces, upper and lower rails secured between the abutment surfaces of said posts, sail rails consisting of sheet metal members having grooves in the plane of the first mentioned grooves, and a panel confined in said grooves. 110 115

2. In a radiator hood, a pair of sheet metal posts having apertured abutment surfaces and grooves inwardly of said surfaces, a pair of spaced hollow sheet metal rails between said abutment surfaces, anchor members in the ends of said rails, each anchor member having a tenon extending thru an abutment surface, a wedge extending thru each tenon, and a panel secured in the grooves of said posts. 120 125

3. In a radiator hood, a pair of sheet metal posts, having abutment surfaces and grooves inwardly of said abutment surfaces, a pair of spaced rails between said abutment surfaces, each rail having a guideway and a 130

groove adjacent said guideway, an anchor member in said guideway and extending thru an abutment surface, a wedge extending thru said anchor member, and a panel supported in the grooves of said posts and rails.

5 In testimony whereof we have hereunto subscribed our names.

PAUL E. SCHLEICHER.
WALTER C. CALCOTT.
